PHILIP DIEHL, OF ELIZABETH, NEW JERSEY, ASSIGNOR TO THE SINGER MANUFACTURING COMPANY, A CORPORATION OF NEW JERSEY.

DRIVING-BELT.

1,202,682.

Specification of Letters Patent. Patented Oct. 24, 1916.

Application filed January 22, 1913. Serial No. 743,439.

To all whom it may concern:

Be it known that I, PHILIP DIEHL, a citizen of the United States, residing at Elizabeth, in the county of Union and State of New Jersey, have invented certain new and useful Improvements in Driving-Belts, of which the following is a specification, reference being had therein to the accompanying drawings.

10 This invention relates to an improvement in driving belts for that class of transmission mechanism known as "sprocket gearing," in which the belt is provided with means to prevent its slipping upon the driving and driven pulleys which it embraces, thereby insuring the preservation of the relative timing of such pulleys and the mechanism operatively connected therewith. This 15 class of mechanism is exemplified in the well-known form of pin-pulley and apertured-belt connection between the needle-actuating and loop-taker actuating shafts of a rotary hook sewing machine, as represented for instance in my United States Patent No. 25 862,240, of August 6, 1907, wherein the pulleys are provided each with two rows of radial pins affording sprocket-teeth entering the apertures of two parallel rows in a connecting leather belt.

30 In the type of sewing machines referred to, the size of the driving pin-pulley upon the upper main-shaft is limited by the width of the hollow bracket-arm affording a support and housing therefor, and the driven 35 pin-pulley upon the loop-taker shaft, rotating at double or treble the speed of the main-shaft, must obviously be much smaller than the driving pulley and in inverse proportion to the relative speeds of the respective 40 shafts. Hence, the connecting belt must be not only very flexible but its pin-apertures accurately spaced apart to prevent injury by imperfect register with the pins of the respective pulleys. The requirements are 45 considerably increased for a belt of this kind when embodied in sewing machines of a more recent construction in which the needle-actuating and loop-taker shafts are turned in opposite directions so as to necessitate the 50 twisting of the belt and the rubbing of the inner faces together in the crossed portions.

In the use of the expedient disclosed in my

said patent, it has been heretofore difficult to secure large quantities of leather sufficiently uniform in quality to stretch equally in all parts in the practical operation of the sewing machine for long periods, and especially when completed belts have been kept in stock for several months preparatory to application to the machine; and this has resulted not infrequently in the unequal stretching of the belt and consequent impairing of the uniformity of spacing of its pin-apertures and consequent destruction of the belt by the imperfect register of the pin-apertures with the pins of the pulleys. Because of the scarcity of the right kind of leather, the cost of such belts has also been excessive for such an element of the mechanism.

70 The present invention therefore has for some of its objects to provide a belt which is thoroughly reliable in use, of moderate cost, and one capable of being twisted to adapt it for transmission of rotary motion from the 75 driving to the driven shaft in the required direction.

To this end, and in its preferred embodiment, the driving belt of the present improvement comprises a laminated band or 80 tape of textile material, such as linen or cotton, of the requisite length to form a series of two or more superposed convolutions with the ends of the plies secured upon those which they overlap by stitching or otherwise, as disclosed for instance in the United States patent to H. E. Smallbone, No. 826,899, dated July 24, 1906. The endless band thus provided is formed with a series of apertures arranged in one or more rows 85 extending lengthwise thereof, and each aperture is entered by a reinforcing eyelet secured in position preferably by two diametrically extending prongs formed at one end thereof and partially overlying the outer 90 face and arranged crosswise of the belt with their end portions thrust through the latter and clenched upon the inner face thereof. By this means the eyelets are secured to the belt for only a portion of their circumference 95 and in such manner that the belt is free to bend relatively to the eyelets which are thus permitted to work slightly inwardly and outwardly through their respective apertures.

The eyelets, while reinforcing the soft yielding edges of the pin-apertures to prevent distortion or enlargement by any imperfect engagement with the pins and protecting the loose ends of the component threads of the fabrics from raveling or fraying, offer no appreciable resistance to the abrupt bending of the belt around the smaller pulley. As the slightly flaring inner ends of the eyelets are in practice made substantially flush with the inner face of the belt and the clenched portions of the fastening prongs are slightly embedded in the same face, such face is substantially smooth so as to produce little noise in the passage of the belt around the usual metallic pulleys which it embraces and to cause no appreciable interference or resistance between the contacting portions of the belt when the latter is twisted.

20 In the accompanying drawings, Figure 1 is a side view and Fig. 2 an edge view of a pair of pin-pulleys connected by a twisted belt embodying the present improvement. Fig. 3 is a perspective view, upon a larger scale, representing a portion of the belt in transverse section, and Fig. 4 is a perspective view of one of the eyelets with its fastening prongs in the condition which they assume when applied to the belt.

30 The larger or driving pulley is shown provided with the hub 1 and rim or face 2 having intermediate the edges a series of spaced conical radial pins 3 affording sprocket-teeth adapted to enter the pin-apertures of the driving belt; and the driven pulley, which is shown herein of one-half the size of the driving pulley, is similarly formed with the hub 4 and rim or face 5 provided with the conical radial pins 6 spaced apart circumferentially correspondingly with those of the driving pulley.

40 The driving belt is shown of laminated type and composed of a tape wound upon itself in a series of convolutions to produce the overlapped plies 7 8 9 which, as represented in Fig. 3, may be secured together by means of lines of stitching 10 arranged parallel with and near the opposite edges. It is obvious, however, that these several plies may be secured together by different means, or that the belt may be woven in a single-ply endless band.

50 As represented in the drawings, the belt is provided with a row of pin-apertures 11 extending around the same intermediate the edges and spaced apart correspondingly with the pins 3 and 6 of the driving and driven pulleys. Each aperture 11 is entered by a metallic reinforcing eyelet 12 whose inner end is slightly flared and terminates substantially flush with the inner face of the belt and whose outer end is formed with a lateral flange 13 having extended diametrically therefrom the prongs 14 bent at right angles intermediate the ends to produce the

members 15 passing through the belt near the edges and having preferably the sharpened end portions 16 which are pressed in the inner face of the belt with their pointed extremities inturned as represented in Fig. 3.

70 As will be observed, the prongs 14 afford narrow fastening strips arranged transversely of the belt for maintaining the eyelets 12 loosely within their respective pin-apertures, and produce little or no resistance to the abrupt bending of the belt around the smaller pulley. These prongs obviously serve to clamp the several plies of the belt together, and may obviously be employed for the purpose without the separate lines 80 of stitching 10, as represented in Figs. 1 and 2 wherein the stitching is omitted.

85 From the foregoing description, it will be seen that the essential feature of the present invention is the application to the driving belt of the reinforcing eyelets secured thereto in such manner that the belt is adapted to bend readily at the pin-apertures independently of the eyelets, the fastening for the latter being effective for only a portion 90 of the circumference thereof. While it is considered preferable to employ fastening prongs arranged diametrically of the eyelets and transversely of the belt, so that the eyelet has unfastened portions at diametrically opposite points lengthwise of the belt, it is evident that other fastening means may be employed within the scope of the present improvement by which the same result may be produced, *i. e.*, that of retaining the eyelet in place while permitting the belt to bend freely relatively thereto at the pin-holes.

95 Having thus set forth the nature of the invention, what I claim herein is:—

1. A driving belt comprising in combination, a flexible endless band formed with a series of spaced apertures disposed lengthwise thereof, and a series of reinforcing eyelets entering said apertures, and each secured to said band at diametrically spaced 105 points along a line lying crosswise of said belt, and being free from attachment to said belt at all other points circumferentially of said eyelet, whereby the band is free to bend 110 about a pulley independently of said eyelets. 115

2. A driving belt comprising a flexible endless band formed with a series of spaced apertures disposed lengthwise thereof, and a series of reinforcing eyelets each entering one of said apertures and formed with supporting prongs extending crosswise of the band and having portions piercing the band near its marginal edges.

120 3. A driving belt comprising in combination a flexible endless band formed with a 125 series of spaced apertures disposed lengthwise thereof, and a series of reinforcing eyelets, each comprising a tubular portion entering an aperture and terminating substantially flush with the inner surface of 130

said band, and securing means disposed wholly in a relatively narrow zone extending crosswise of said belt and diametrically of an aperture, for holding each eyelet in position while permitting bending movements of the belt relatively to each eyelet.

In testimony whereof, I have signed my

name to this specification, in the presence of two subscribing witnesses.

PHILIP DIEHL.
